TOY

Henry A. James, Orlando, Fla., assignor of one-half to
John M. Blanton, Orlando, Fla.

Application August 18, 1955, Serial No. 529,109

5 Claims. (Cl. 104—73)

This invention relates to a toy and particularly to a toy having a water course for the conduct of toy ships, boats, barges and other toy floating equipment.

The primary object of this invention is the provision of an improved water toy.

Another object of the invention is the provision of an improved water toy having a water course for the travel of toy ships, boats, barges and other floating equipment.

Another object of the invention is the provision of an improved toy having a waterway or channel for the circulation of water, in which the direction of the water flow can be controlled by the operator.

Another object of the invention is the provision of an improved toy having a waterway or channel for the circulation of water in which there are diversion channels to pass the water through one course or another at the option of the user.

Another object of the invention is the provision of an improved water toy having a water course for conducting ships, boats and the like and being constructed of sections which are separable from the other sections.

A further object of the invention is the provision of an improved water toy having detachable sections which may be replaced by other similar or differently shaped sections to produce different forms of the water course to suit the aims or desires of the user.

Still another object of the invention is the provision of an improved water toy having a water course and detachable sections, one section of which is provided with an outlet to a water pump, a delivery conduit being provided to deliver water from the pump to the water course.

A still further object of the invention is the provision of an improved water toy having a water course for the travel of toy ships, boats and the like, there being means for causing the water to move along the water course and a means for slowing down the speed of the water in the water course at a desired docking space.

Another and further object of the invention is the provision of an improved water toy having a water course for the travel of toy ships, boats and the like and having sectional pieces to provide for the expansion and contraction and changing of the shape of the water course.

Another and still further object of the invention is the provision of an improved water toy having a water course for the travel of toy ships, boats and the like and means for causing the water to travel in either direction in the water course.

Still another object of the invention is the provision of an improved water toy having a water course, detachable and selectively connecting sections for varying the size and contour of the water course and means in the water course to vary the speed of flow in a selected section.

A still further object of the invention is the provision of an improved water toy having a water course, detachable and selectively connecting sections for varying the size and shape of the water course to vary the speed of flow of the water in a selected section and gate means for selectively directing a faster flow of water into one of a

2

plurality of sections and slowing the flow, correspondingly in another section.

Other and further objects of the invention will be apparent to those skilled in the art from a reading of the complete specification.

Referring to the drawing wherein is illustrated an embodiment of my invention,

Fig. 1 is a plan view of my invention illustrating one combination of detachable and selective sections as may be selected by a user.

Fig. 2 is an elevation of the construction illustrated in Fig. 1.

Fig. 3 is a sectional view on the line 3—3 of Fig. 1.

Fig. 4 is a detail view of the gate locking device of gate 32x in elevation.

Fig. 4a is a similar view of the gate 33x but in separated position as when changing the adjustment.

Fig. 5 is a detail sectional view of three course sections with a 90° section 31 between the other two sections.

Fig. 6 is an elevational view of one of the 90° sections 31.

Fig. 7 is a perspective view of one of the clamps 35 which holds the sections together to make the joints water tight.

Fig. 8 is a diagrammatic showing of the water power-unit and its electric motor, for furnishing the water delivery under pressure to move the water in the water course and the top ships, boats, and the like floating on the water.

Figs. 9, 10 and 11 are detail views of one type of water delivery jet for use with my invention.

Fig. 12 is a sectional view of a portion of the wall of a section of the waterway illustrating the front of a movable jet and its supply pipe.

Fig. 13 is a separated view of the parts of a movable jet.

Fig. 14 is a cross-sectional view on the line 14—14 of Fig. 13.

Fig. 15 is a vertical cross-section of the jet 38.

Fig. 16 is a cross-section on the line 16—16 of the jet shown in Fig. 15.

Fig. 17 is a cross-section on the line 17—17 of Fig. 15.

Fig. 18 is a detail view taken from about on the line 18—18 of Fig. 1 showing some parts in section.

Fig. 19 is a detail view of the gate 51d having a pintle 51e and a locking detent 51h which cooperate with the openings 51f and 51k of Fig. 20.

Fig. 20 is a detail sectional view similar to a part of Fig. 18.

The invention broadly relates to a toy waterway which, because it is built up in sections, is adapted for modification and changes to vary the outline and uses of the toy as a whole. The construction is such that a child who uses the toy may, by the substitution of different types of sections, alter not only the construction but the uses to which the parts of the toy may be put in simulation of the movement of ships and other toy marine vehicles. In this way, freedom of the imagination of the child is given and his educational development is accelerated.

The present embodiment of the invention has a basic or main section upon which the whole structure is based and in which are located some of the most important parts of the construction.

Similar reference characters refer to the same or similar parts.

Referring particularly to Figs. 1 and 2 of the drawing, the basic section, broadly, is designated by the reference character 30. This basic section has an inflow opening 30a and an outflow opening 30b. The device as a whole has a flow circuit in which water or other liquid passes through a course from any given point around its course returning to the same place or a similar place, carrying

toy boats, ships or other floating objects along with the flow of liquid.

In the embodiment shown, the basic section 30 is connected to a course end section 31 at its inflow end and a switch section 51 at its outflow end. These sections 31 and 51 have some common features in their construction and have water-tight connection with the basic section 30, as will be described. In the construction shown, the water or other liquid flows in a counter-clockwise direction but this direction may be changed and reversed, as will later be made clear.

The sections 31 are in the form of 90° elbows, two of which, as shown, make a complete 180° change in the direction of flow in the water-course. Connected to the ends of the elbow members 31 and completing one end of the course as illustrated, is a straight section 32 which, as shown, is of the same length as the basic section 30.

The basic section 30 may be made in any suitable shape as that shown in Figs. 1 and 2. Fig. 1, which is a plan view, shows alternate courses for the toy boats, ships or other floating craft used with the toy waterway. One of these courses I have designated by the reference character 30x and the other by the character 30y. Either may be used as a section of the main course and the other as a harbor or docking place, at the will of the operator.

In order to control the selection of the course section—30x or 30y—and have the floating equipment pass into the proper section of the passage in the course, I provide a gate 32x, 33x at each end, as shown in Fig. 1. These gates are pivoted on vertical pivots 32a, 33a and extend deep enough into the water to direct most of the water into the selected course section 30x, 30y as the case may be. The gates 32x, 33x extend preferably to a height sufficient to show above the water-level, so that the position of each gate may be clear at all times.

Between the course sections 30x and 30y is a separating platform 30c which is tapered at each end where the sides come together at the pivots 32a, 33a and the gates 32x and 33x form, alternately, the walls of the courses 30x and 30y, depending upon the setting of the gates 32x and 33x. The horizontal platform 30c may be used as a dock for the ships or boats.

The gate pivots 32a, 33a are, respectively, provided with levers 32b, 33b, by means of which the gates 32x, 33x are swung from side to side. At the outer ends of the respective levers 32b, 33b are suitable locking devices as the detents 32c, 33c, as shown in elevation in Fig. 4. These detents 32c, 33c are in position to engage appropriately placed openings, as 30d, in the separating wall 30c, to hold the respective gates 32x, 33x in either of the adjusted positions, as desired. In this way, the water may be deflected to either course 30x or 30y, as desired. In the bottom of the two course sections 30x and 30y, are holes or openings 30e which communicate with a reservoir or collecting box 34 which is clearly shown in plan in Fig. 1. The purpose of this collecting box 34 is to take sufficient water from the course sections 30x and 30y to supply the water pump which will be later described. In Fig. 2 is shown an outlet delivery conduit 34a which conducts the water to the pump as will be later described. This removal of the water slows the water flow through section 30.

As already indicated, the course sections 30x and 30y have a common inlet and a common outlet, each of which is, respectively, controlled by the gates 32x and 33x. The common connections at the ends of the basic section 30 are similar to the connections at the ends of the right angular sections 31 and the straight section 32 to enable the operator to obtain a water-tight connection between the several sections and thus assuring the holding of the water in its course during use. The construction of these connections will now be described.

Each of the sections 30, 31 and 32, is provided with an outwardly projecting flange at each end as at 30f, 31f and 32f, to abut with the similar and coacting flange of

the adjacent section 31, 32, 30, as shown in Figs. 1, 2, 5 and 6.

These flanges are continuous and extend in a vertical plane from the ends of the course sections above the water line, down along the sides and bottom of the sections' ends. Suitably secured to the outer faces of the flanges are packing strips, as of soft rubber, which are illustrated at 31g in Figs. 5 and 6. In order to hold the flanges 30f, 31f and 32f in close water-tight relation with the adjacent course section, a suitable clamping means as 35 has been provided. This clamping member 35 is illustrated in Figs. 1, 2, 5 and 6 in assembled position and in detail detached position in Fig. 7. This clamping means 35 has a general shape similar to the flanges 30f, 31f, 32f, with a U-shape cross section, the open end of the U being placed inwardly to receive the flanges 30f, 31f, 32f of the adjacent sections. The open space of the U is such that when the U-shape clamping means 35 is in place, the packing means of each flange will be pressed against the similar packing means of the adjacent flange to make the joint water-tight. It is to be understood, of course, that the slot of the U-shape member is deep enough to receive both of the flanges of adjacent course sections and their packing means, thus holding the flanges in proper relation. The clamping means 35 is shown, although not necessarily so, as being constructed in one piece.

In order to cause the water to flow along the water-course, I provide a water pump and a suitable motor to provide for its operation. This power plant will now be described.

The water delivery conduit 34a conducts the water to the intake 36a of the water pump 36 which is located adjacent its shaft. As the blades of the water pump turn, the water by centrifugal action, is forced outwardly, where it emerges from the housing of the pump 36 at 36b. A control unit 37, which is shown in Fig. 8, receives the water from the water pump 36 and serves as a distribution means by which the movements of the water through the water course, are determined. This distribution means will now be described.

My invention contemplates the use of integral and detachable outlet means for the water by which the water is admitted to the water course under pressure at the desired points but is under control of the operator as to the delivery pressure and the direction of delivery. For this purpose, delivery jets are provided which, by their construction, may deliver the water at the desired points and be directionally pointed to force the water in the water course in the desired direction, and at the desired pressure.

For carrying out this water delivery, I provide delivery jets, some of which may be a part of the course sections and others which are movable may be provided to deliver additional water under pressure at desired points. The needs of the different parts of the system may require different amounts of water to be delivered, depending upon the particular combination of types of sections and their number and arrangement in the set-up.

Referring particularly to Fig. 1, it will be seen that I have illustrated one type of jet at some points of the course and another type at other points. The rigid type will first be described. In Figs. 1, 9, 10 and 11, I have shown the outside wall of one of the course sections 32, 65 as having a slight bulge 32h in which the jets are secured, as by welding. Each tube 32g is connected by a flexible tube 32m to one of the selective outlets 37a of the control unit 37, already described. Each of the outlets 37a is connected to a selective valve 37b which controls the entrance of the water from the interior of the control unit 37 and for delivery to either one of the jets 32k as determined by the two-way valve 32n. Summarizing, with the valve 32n set to determine the direction of flow of the water along the water course, the jet 32k for that

particular valve will receive water under pressure when its valve 37b is opened.

At places where it may be expected more or less delivery from the propulsion jets may be desired, depending upon the arrangement of the course sections, I have provided a movable jet unit as shown at the lower side of the course section 32 in Fig. 1 and also in detail in Figs. 12, 13, 14, 15 and 16. A jet body 38 is of a flattened tubular construction and has a vertical opening 38a at one edge as shown in Figs. 12, 13, 14 and 15. The top of the jet member 38 is provided with a slightly tapered opening 38b to receive the end of a bent tubular member 39 having a tapered end 39a, to fit tightly in the tapered opening 38b of the jet member. This construction enables the operator to set the jet opening 38a so as to point in any direction throughout 180°. The tubular member 39 is provided with an off-set bend 39b, which, when in place, will bear against the outside of the wall of the course section to which it is attached and hold the jet assembly in place. The receiving end 39c of the tubular member 39 is attached to one of the flexible tubes 32m and is controlled in its water delivery, through its particular valve 37b, as already described. From the illustration in Figs. 12, 13, 14, 15 and 16, it will be clear that the jet member 38 may be placed in either position substantially 180° apart or in any direction therebetween to deliver the water under pressure in the desired direction, and the resiliency of the tubular member 39 and its off-set bend 39b pressing against the wall of the course section will hold the jet assembly in position during operation.

It will be observed that with the well-known construction of the two-way valve, any valve 32n may be placed on a dead spot so that no delivery can take place from its jet 32k. The same condition exists when its valve 37b is closed.

At the right side of Fig. 1 are illustrated other forms of course sections which serve to give the user of my invention another type of alternative course for the water, depending upon which way the directing gates are set for operation. These alternative courses for the water travel and the consequent alternative travel routes of the ships and boats make the use of the toy more interesting and instructive.

The sections 50 and 51 designate generally these sections and comprise what might be termed a combination of short straight sections 50a, 51a each with an angular 90° turn similar to the angular sections 31 already described. It will be noted that when one section, as 50, is used, it may be convenient in many situations to make use of another similar section 51 as a complement, the two sections being constructed with their angular sections 50b, 51b turned in relatively opposite directions, as shown.

The sections 50 and 51, each have three flanges for connection to adjacent sections. These flanges are all similar in construction to the section flanges already described and are respectively designated 50c, 51c. With this construction, it is clear that the outlets for the respective sections will be in position for connection to other sections as, for example, the sections 30, 31, 32.

When connected in the system the water course through the sections 50, 51 will have cross-sections similar to the cross-section of, for example, the corner sections 31.

Many variations in the form and size of the set-up will be apparent. For example, two straight sections as 32 may be placed between the right ends of the portions 50a, 51a and the left ends of the angular sections 31 at the right side of the system, which would extend the water course as a whole, to the right a distance equal to the length of a section 32. Another manner of increasing the size of the system would be to utilize three sections such as the section 32 by connecting one section 32 between each of the pairs of sections 31 at the right and left of the set-up and the third section between the

portions 50b and 51b. Various ways of changing the size and shape of the water course will be apparent to the user.

Wherever there is an alternative route provided in the water course, it is desirable, though in some cases not absolutely necessary, to also provide switching gates to direct the water in the proper course. In order to keep the cross-section of the water course substantially the same, and still provide for direction of the water either in a straight direction or around a curve, a specially shaped curved gate is provided. This gate will now be described.

At the angle between the portions 50a and 50b of the section 50 and the corresponding place on the section 51 are provided recessed places to receive the pivoting portions of the gates 50d, 51d. Vertical pivots 50e, 51e are provided on the gates to be received into the openings 50f, 51f. These pivots are of a size to fit snugly in the openings 50f, 51f.

Extending from the gates are adjusting arms 50g, 51g which have at their ends, downwardly extending detents 50h, 51h. These detents 50h, 51h are so placed as to register with openings 50k, 51k which are located in bulges 50m, 51m at appropriate places in the upper edges of the walls of the sections 50, 51. By simply lifting the gates 50d, 51d to clear the detents from their openings 50k, 51k, the gates may be moved to the dotted positions shown in Fig. 1 and the route of the water will be changed to another course. By lowering the gates, the other openings 50k, 51k will be engaged by the detents 50h, 51h and the gates 50d, 51d will be held in the new positions.

Since one part of the sections 50, 51 is straight and the other part is curved, the gates are curved to an extent not as much as the curved sections 50b, 51b are curved. This will retain the cross-sections of the water course at the several points so near to constant that for practical purposes, it is constant. By maintaining a substantially constant cross-section for the water flow, there is a minimum of eddy currents formed to alter the course of the water.

It is to be understood that the pressure and the consequent volume of the water may be controlled by varying the setting of the valve 37b for any particular jet opening for either type of jet.

The power for the water pump is, as already indicated, supplied by the electric motor 40. Power for this motor is supplied by electrical connection to any suitable source of power. In practice, for the use of children, the current may be supplied from the usual and well-known transformers which supply low voltage current and are designed and built for this purpose. A suitable switch, not shown, is provided for connecting the current supply with the motor.

I will now describe the operation, in general. Having determined what course-units will be used in the set-up, these are placed in juxtaposition and secured together in the manner already described. The clamping means 35 are put into position to hold the sections together. Water is now placed in the water course and the joints checked for leaks.

The gates 32x and 33x, 50d and 51d are set to cause the water in the water course, to pass through the passage 30x or 30y. The boats or ships are placed in the water. The electric motor is now started. The jets should now be checked to see that their openings are all pointed in the direction in which it is intended the water should travel. As the ship or boat approaches the gate 32x, it may be found desirable to have a jet to direct the floating unit to the right as shown in Fig. 1. To facilitate this placing, the bulges, as 32h, in the sides of the course sections are spaced wherever it may be found desirable under any conditions, to place a movable jet.

If it is desired by the operator to reverse the flow of the water, all jets or part of the jets may be reversed so that the water will travel in the opposite direction. If

it is desired to have the ships follow the course-section 30x instead of the course-section 30y, the gates 32x and 33x are placed in their alternate positions. By reversing the intake gate when a ship is in the section 30y, the movement of the ship will be slowed or stopped. Upon reversing the gate 33x, the ship will definitely stop, whereupon it may be secured to the dock-side in the manner of a full-size vessel.

If it is desired to have the water in its course merely slow its speed in both alternative portions as 30x, 30y, rather than have the water in one portion go faster than another, it is only necessary to move the gates 32x, 33x. This will permit a portion of the water to go in one alternative course portion and the remainder in the other. In a like manner, the gates 50d and 51d may be removed 15 with similar results.

In order to make the toy more interesting and realistic, it is to be understood that accessories such as miniature lighthouses, docks, power houses for covering the motor and pump may be provided. However, since these are 20 not a part of this invention per se, it is not thought necessary to illustrate them in detail.

The parts of this invention may be made of any well-known or suitable material such as any of the various suitable plastics, white metal or sheet metal, and they 25 may be made by any of the suitable methods by which the selected material is made.

The ships or boats designated as S may be made of any suitable material and constructed by any suitable process and of a size and type suitable to the width and 30 depth of waterway for which the parts carrying the water course are designed for the market.

While one embodiment of my invention has been illustrated and described in detail, it to be understood that the disclosure is merely illustrative and that many modifications and changes to produce interesting and instructive results may be made without departing from the spirit of the invention and within its scope as claimed.

Having described my invention, what I claim is:

1. A toy having a waterway, means connected to said 40 waterway including a pump for moving water in the waterway and having a plurality of nozzles, each connected to said pump and said waterway at variably spaced intervals therealong, each of said nozzles having independent stream-directing means adjustably mounted thereon for selectively discharging water from the nozzle into 45

the waterway in any one of a plurality of horizontal directions corresponding to the adjusted position of the stream-directing means relative to the nozzle.

2. A structure according to claim 1 and having the waterway provided with side walls, indentations therein with each of said nozzles being secured therein.

3. A structure according to claim 1 and having a compact central control station, having separate water conduit outlet connections to various ones of said nozzles and a connection from the discharge side of the pump, and said station having means for varying the supply pressure of the water at any nozzle relative to and independently of any other nozzle.

4. A structure according to claim 1 and said waterway having means for dividing said waterway into a plurality of sections, each of said waterway sections having a discharge outlet connection to the pump, to remove water from the divided sections to thereby decrease the amount of water flowing through the waterway and slow the movement of water in the divided sections.

5. A structure according to claim 1 and having separable sections for lengthening or shortening the waterway and gates pivotally mounted on the walls of the waterway for controllably switching the flow of water in the waterway and shaped to conform to the sides of the waterway to maintain the same at a constant cross section when the gates are at either ends of their limits of position.
